UNITED STATES PATENT OFFICE

ROBERT ERNEST HEATH, OF MONROE, NORTH CAROLINA

PORTABLE VENDING MACHINE

Application filed March 29, 1929. Serial No. 351,018.

This invention relates to a portable vending structure in the form of a wheel supported conveyance constructed to provide a satisfactory form of vehicle for facilitating 5 display and dispensing of merchandise and commodities of the domestic species.

More specifically stated, the invention has reference to a novel structural organization of parts, such as may be embodied in a complete vehicle or employed as an auxiliary trailer, the same embodying a multiple arrangement of article supporting shelves assembled into distinct sections and so co-related as to expedite access and sale and to 15 provide a convenience and compactness of arrangement in order to adapt the structure for city and community service.

The particular details and their special cooperation and association will become more 20 readily apparent from the following description and drawings.

In the drawings:

Figure 1 is a top plan view of the complete structural arrangement embodied in a vehicle.

Figure 2 is a side elevational view with one of the longitudinal side sections swung to open position.

Figure 3 is a top plan view of the base portion of the structure.

Figure 4 is a vertical section on the line 4-4 of Figure 1.

Figure 5 is a sectional view, taken approximately upon the plane of the line 5-5 of Figure 6, and

Figure 6 is a cross section taken on the line 6-6 of Figure 3.

The complete and general arrangement of parts may be readily seen in Figure 4. Here 40 the reference character 7 designates generally a body which is constructed to provide an enclosure for a plurality of individual and distinct sections. The reference characters 8 designate spaced parallel rigid sections defining a compartment 9, which may be distinguished as a central housing for a relatively 45 slidable section 10, this normally being confined in telescopic relation between the sections 8. The sections 8 include individual 50 shelves 11, and the section 9 includes shelves

12 arranged on opposite sides of the division or partition piece 13. The reference characters 14 designate generally outer side sections having outer closing walls 15, and hingedly mounted to permit the swinging of the sections outwardly to the positions shown in Figure 2. In this connection, it will be observed that the reference character 16 designates the base frame, located beneath the rigid section 8 and the swingable sections 14. 55 These are spaced apart on opposite sides of the central floor portion 17, and the inner longitudinal members of these frames 16, carry longitudinal stringers 18 which define longitudinal runways as seen in Figure 5. Reference being had to the last named figure, it will be observed that middle tracks 19 are arranged in these runways, and that longitudinal rails 19 on opposite sides of the telescoping section 9 are confined in these runways and carry rollers 20, which are movable on the tracks. Thus the complete section 9 may be slid to the rearwardly extended position shown in Figure 1. Incidentally, this 60 slideable section 9 is provided with hinged closing doors 21, for the shelves 12.

The reference characters 22 designate hingedly mounted awnings associated with the body portion 7 of the structure. Then, too, the reference characters 23 designate 65 similar but smaller awnings which are associated with the slideable section 9. These awnings 23 are disposed on opposite sides of and connected with a roofing awning portion 24, this in turn being connected with the body portion in a manner to permit it to be 70 swung downwardly to effect a closure.

The portions 23 and 24 provide a multiple part auxiliary awning, of such construction that the portions 23 may be swung down and telescoped into the compartment 9, when the slideable section 10 is slid therein. Then, too, the portion 24 effects a closure for the rear end of the structure defined. Thus, this auxiliary awning for the extensible shelf section 95 10 has a double function.

In addition to the shelf section and the awning, I provide means for operating the relatively slidable or telescopic section 10 and this comprises a windlass generally des- 100

gnated by the reference character 25 in Figure 3. This is provided with an operating crank 26. Associated therewith is a cable, one end portion 27 of which is connected with the inner portion 28 of the slideable section 5 and wound around the windlass and the other end portion of which is passed over a stationary pulley 29 and anchored to the front portion as at 30. Thus, by turning the hand crank 36 in one direction, the section 10 may be fed outwardly, whereas by turning it in the opposite direction, the section may be retracted into the housing. In order to steady the operation of the slideable section, 15 an additional cable 31 is provided, it being wound on the windlass and extending up over a pulley 32 as shown in Figure 2, and connected with the top of the slideable section as at 33. This prevents sagging of the section 20 when it is extended to the position shown in Figures 1 and 2. Thus, a mechanical manually manipulated means is afforded for projected or retracting the central slideable shelf section 10. Of course, the track and the complementary stringers and rails facilitate the operation and aid in the rigidity 25 of arrangement.

The gist of the invention is embodied in a portable structural arrangement embodying 30 a pair of spaced parallel rigid sections defining a compartment for the reception of a relatively slideable section, and hingedly mounted side sections serving as closures for the rigid sections.

35 In this way, the hinged sections may be swung out to expose the contents of their respective shelves, and to simultaneously expose the contents of the shelves of the rigid section. The display is amplified by the 40 presence of the slideable section having shelves on the opposite sides of the partition enclosed by individual doors or closures.

A careful consideration of the description in conjunction with the drawings will enable 45 a reader to obtain a clear understanding of the construction and arrangement as well as the features and advantages.

Therefore, a more lengthy description is regarded as unnecessary.

50 Minor changes in the shape, size, materials and rearrangement of details may be resorted to, within the scope of the adjoined claims, if desired.

I claim:

55 1. In a portable carrier and display structure of the class described, a pair of spaced parallel relatively stationary shelf sections defining a central compartment, a closure for the outside of each shelf section, a pair of 60 relatively movable sections equipped with shelves and hingedly mounted upon said relatively stationary sections, and an extensible section telescopically confined in said compartment.

65 2. In a portable vending structure of the

class described, a body including a base, relatively fixed shelf sections mounted on said base and disposed in spaced parallelism and defining an intervening central compartment, swingable shelf sections mounted on 70 said fixed sections and adapted to swing outwardly to open position to simultaneously expose the contents of the shelves on said fixed sections and swingable sections, tracks in said compartment, and a slideable shelf section including rollers slideable on said tracks, and individual awnings for said swingable section and said slideable section, the awnings for the slideable section having the additional function of closing means 75 when the slideable section is telescoped into the compartment.

In testimony whereof I affix my signature.

ROBERT ERNEST HEATH.
